UNITED STATES PATENT OFFICE.

ERNEST NICKERSON, OF NEWTON, MASSACHUSETTS.

FORM FOR MAKING HOLES OR CONDUITS IN CONCRETE OR OTHER STRUCTURES.

SPECIFICATION forming part of Letters Patent No. 752,249, dated February 16, 1904.

Application filed October 17, 1903. Serial No. 177,440 (No model.)

To all whom it may concern:

Be it known that I, ERNEST NICKERSON, a citizen of the United States, and a resident of Newton, in the county of Middlesex and State of Massachusetts, have invented a new and useful Improvement in Forms for Making Holes or Conduits in Concrete or other Structures, of which the following is a full, clear, and exact description, reference being had to the accompanying drawings, forming a part of this specification, in explaining its nature.

My invention relates to a form to be used in making holes or conduits in concrete and other structures. It is embodied in a construction which can best be seen and understood by reference to the drawings forming a part of this specification, wherein—

Figure 1 shows the improved form in vertical longitudinal section taken through its center. Fig. 2 shows the same in longitudinal horizontal section. Fig. 3 shows a cross-section on the line 3 3 of Fig. 1, and Fig. 4 shows a cross-section on the line 4 4 of Fig. 1.

I will first refer to the improved form as complete, describing its various parts or elements of structure, and then refer more specifically to the form with respect to the peculiar efficiency of construction, especially as regards the facility with which its various parts or elements may be put together preparatory to the work being done and after the work has been done the facility with which the form can be knocked down and withdrawn from the hole or conduit formed in the concrete or other substance.

In the drawings the outside of the form consists of strips of lagging or sheathing A. The various sections are arranged cylindrically and laid to project in the direction in which it is desired to make or extend the opening. In this connection it is to be noted that although the form is shown as embodied in a cylindrical arrangement of the sheaves or lagging designed to make a rounded hole, yet this arrangement is but arbitrary, representing its more common embodiment, which may well be changed, dependent upon the shape of the hole or conduit desired to be formed. One of the strips of lagging a is shaped like a wedge, and the edges of its two adjoining strips or

sections are cut to fit this wedge-shaped strip when introduced. This is to facilitate the removal of the lagging after the hole or conduit has been formed by the withdrawal of the wedge-shaped strip, but to this reference will 55 hereinafter be made.

The respective sheaves or strips of lagging are held in place by means of inside pieces B. These are made of relatively narrow pieces of wood and have segmental shape in order that 60 their rounding edges may give bearing or support to the lagging or sheathing on the inside, for, as stated before, my improved form is embodied in a cylindrical disposition of the sheaves or lagging adapted to make a rounding hole, although of course the sheaves or lagging might well have some other arrangement, when the inside pieces B will be shaped to conform thereto. Referring, however, to the pieces B as "segmental" pieces, it will be 65 noted that these pieces are arranged with their straight edges parallelly disposed and somewhat separated from one another when the segmental pieces are in place. Two or more sets of these segmental pieces are required, 70 and they will be spaced at such distances that the lagging will be supported sufficiently to prevent its bending under the weight of the concrete or other material built around it.

Interposed within the space left between 80 the separated edges of the respective sets of segmental pieces and placed to bear against and so to support the adjacent sheathing are side pieces B', which are held in place against longitudinal movement by flanges b, secured 85 to the adjoining portions of the segmental pieces B, which flanges act as stops upon either side to hold the side pieces in place against longitudinal movement, as before described, but permitting of their being drawn in laterally, and it is especially to be noted that the retention of the flanges b is such that after the side pieces have been moved in laterally a certain amount they will be drawn clear of the flanges b and may then be moved longitudinally or lengthwise the hole. Between these respective side pieces and resting upon the lower segmental pieces are placed a series 90 of members comprising a central wedge-shaped member C and two side members C' 95 100

C' , having inclined sides which lie contiguous with the inclined sides of the wedge-shaped member interposed between them. These side members bear along their outer sides 5 against the side pieces B' , to which they are secured by nails b' or any other suitable means of connection. These side pieces might be formed as an integral part of the side members $C' C'$, for practically when combined with 10 the flanges b they serve as a means of retention to the side members $C' C'$ for holding the same in place against else than a lateral movement except when said side pieces are moved laterally to a certain position, when 15 said side members are capable of longitudinal movement. I much prefer, however, to form the side pieces as separate parts, as before described.

The members $CC' C'$ are best made of wood 20 and preferably bear such relation to each other along their inclined or sloping sides that when the central wedge-shaped member C is half withdrawn in a direction parallel with the axis of the hole from between the side 25 members $C' C'$ then the lateral distance traveled by the side of the wedge-shaped member will be equal to the lateral distance traversed by the side pieces B before they become drawn clear of the flanges b , which normally 30 hold them against longitudinal movement, as before described; but the central wedge-shaped member C is so secured to its side members $C' C'$ that they are held in place against longitudinal movement by their connection with the side pieces B' , retained by 35 their respective flanges, and will be drawn in laterally as the central member C is drawn out or until the side pieces B' have cleared the flanges which hold them, which happens 40 when the central wedge-shaped member is about half withdrawn, for, as stated before, the radial distance traveled by the side of said member will be equal to the space traversed by the side pieces B' before they are drawn clear 45 of the flanges which hold them. The central wedge-shaped member C is accordingly fitted with top and bottom plates c , which plates extend out laterally from along its inclined sides with the ends of the respective plates turned 50 in to lie in an alignment parallel with the inclined side edges of said central member C and its adjacent side members. These turned edges of the plates c extend into grooves c' , formed in the respective side members, the 55 mechanical effect being that when the central wedge-shaped member C is withdrawn it will draw the respective side members $C' C'$ in laterally by means of these connecting-plates, for, as before stated, the side members are 60 held longitudinally fixed by being supported to the side pieces B' , which are held by the flanges b , and this lateral in-drawing of the side members and attached pieces is continued until the side pieces are drawn clear of the re-

taining-flanges b , when the side members, no 65 longer being held fixed, will move longitudinally with the central member C and all may be drawn out together.

The central wedge-shaped member C has a groove c^2 running longitudinally along its under side. This groove fits loosely over a pin c^3 , which is driven into the top of the lower segmental piece B , and thus the member C is guided in its drawing movement with respect to the side members an equal amount on both 75 sides. This construction of form is exceedingly simple and inexpensive. There is no complexity of parts—nothing that can break or easily wear out. It is capable of repeated usage.

Referring to the facility with which the form can be used, I will first speak of the way in which it is built up preparatory to making a hole or conduit in concrete or other structure. Supposing that it is desired to form an opening through a wall of concrete, when the grade of the top of the concrete approaches the grade of the bottom of the opening which it is desired to form, the top is first leveled off. If the desired hole is a continuation of one already existing, the lower sections of the lagging or sheathing A are laid into the end of the same, projecting in the direction in which it is desired to extend the opening; otherwise the free ends of the lagging or sheathing are supported in their correct position by any suitable profile. The under segmental pieces B are then placed on edge within the placed lagging or sheathing, said segmental pieces being spaced from one another to 85 properly support the sheathing, as before stated. The side pieces B' are then slipped into their places between the retaining-flanges b of the lower segmental pieces B and they are placed to bear against and to so support that portion of the sheathing or lagging to which they are adjacent. The central wedge-shaped member C is then put in place, resting upon the lower segmental pieces B , and the two side members $C' C'$ slid into place on either side 90 thereof to bear flush up against the side pieces B' . The side pieces are then nailed to said side members—that is, if made in separate parts, as they preferably are. The upper segmental pieces B are then put in place, their flanges b fitting down over the side pieces B' and so supplementing the flanges b upon the lower segmental pieces and holding said side pieces B' 95 in place. The remaining lagging is then built over the upper segmental form and with the wedge-shaped piece a held in place with a string or other suitable band. The concrete or other structure is then built over the form. After it is set the central wedge-shaped member C is drawn out, which by means of its connecting-plates c has the effect of drawing 100 laterally the side members $C' C'$, as also the side pieces B' , to which the side members

are secured. Such lateral indrawing is continued until said side pieces are drawn free of the flanges *b*, which hold them fixed in place, when all the members and the attached side pieces can be drawn out longitudinally together. The segmental pieces are then taken out and loosen the sheathing or lagging.

With respect to the sheathing or lagging the cement as it sets might have a tendency to contract and so bind the lagging or sheathing, but by means of the wedge-shaped piece of sheathing *a* this can be first pulled out, whereupon the remaining sections of sheathing or lagging collapse.

What I claim as my invention is—

1. A form of the character specified, comprising strips of lagging or sheathing, inside pieces for supporting the same, said pieces interposed between the separated edges of said inside pieces, means of retention for holding said side pieces in place against else than a lateral movement except when said side pieces are moved laterally to a certain position when they may be moved longitudinally, a wedge-shaped member and means for combining said wedge-shaped member with said side pieces that the same may be drawn in laterally by the inclined sides of the wedge-shaped member as said member is drawn out longitudinally, and when said side pieces are drawn in to a certain lateral position then they may be drawn out longitudinally with said wedge-shaped member.

2. A form of the character specified, comprising strips of lagging or sheathing, inside pieces for supporting the same, side members interposed to extend longitudinally between the separated edges of said inside pieces, means of retention for holding said side members in place against else than a lateral movement except when said side members are moved laterally to a certain position when they may be moved longitudinally, a wedge-shaped member and means for combining said wedge-shaped member with said side members that the same may be drawn in laterally by the inclined sides of the wedge-shaped member as said member is drawn out longitudinally, and when said side members are drawn in to a certain lateral position they may then be drawn out longitudinally with said wedge-shaped member.

3. A form of the character specified, comprising strips of lagging or sheathing, inside pieces for supporting the same, members with inclined sides extending longitudinally between the separated edges of said inside pieces, means of holding said members in place against else than a lateral movement except when said members have been moved in laterally to a certain position, a central member having inclined sides adapted to be placed between and with its inclined sides contiguous with the inclined sides of the aforesaid members, and

means for combining said members along their inclined edges permitting, however, of the central member having longitudinal movement relatively to its side members when they are held fixed.

4. A form of the character specified, comprising strips of lagging or sheathing, inside pieces for supporting the same, members with inclined sides extending along and interposed between the separated edges of said inside pieces, means for holding said members in place against else than a lateral movement except when said members are moved laterally to a certain position, a wedge-shaped member interposed between and longitudinally extending with inclined sides contiguous with the inclined sides of said members aforesaid, and plates with turned edges for combining said members along their inclined sides, substantially as described.

5. A form of the character specified comprising strips of lagging or sheathing, inside pieces for supporting the same, side members interposed to extend longitudinally between the separated edges of said inside pieces, means of retention for holding said side members in place against else than a lateral movement except when said side members are moved laterally to a certain position, when they may be moved longitudinally, a central wedge-shaped member having inclined sides adapted to be placed between and with its inclined sides contiguous with the sides of the aforesaid side members, means for combining said members along their inclined sides, permitting, however, of the central member having longitudinal movement relatively to its side members when they are held fixed, and means for guiding said central member that it may be drawn out upon the same line of longitudinal movement.

6. In a form of the character specified, the combination of strips of lagging or sheathing, inside pieces *B* for supporting the same, a wedge-shaped member *C* interposed to extend longitudinally between the separated edges, longitudinally-extending side members *C', C'*, means for holding said side members in place against else than a lateral movement except when said members have been moved in laterally to a certain position, and plates *c* for combining said members along their inclined edges, substantially as and for the purposes set forth.

7. In a form of the character specified, the combination of strips of lagging or sheathing, inside segmental pieces for supporting the same, side pieces *B'*, flanges secured to said inside segmental pieces for holding said side pieces in place against else than a lateral movement except when said members have been moved in laterally to a certain position, a series of members *C, C', C'*, longitudinally extending and interposed between said side

pieces to which said members C, C' are secured, means for combining said members along their inclined edges, permitting, however, of the central member C having longitudinal movement relatively to its side members when they are held fixed, and a pin secured to the under segmental piece B adapted to run in a

groove formed in the central wedge-shaped member C, substantially as and for the purposes set forth.

ERNEST NICKERSON.
